STACKING MECHANISM

Robert Alonzo Williams, Chicago, Ill., assignor to
Ditto, Incorporated, Chicago, Ill., a corporation
of West Virginia

Application August 9, 1941, Serial No. 406,209

13 Claims. (Cl. 198—35)

This invention relates to counting and unloading tables for unit strips such as are produced by the machine of my prior Patent No. 2,238,356, dated April 15, 1941, the present apparatus being designed particularly for use as an extended portion of the machine of the patent. It is the object of the invention to provide an improved arrangement of cooperating parts by which a series of products such as the units produced by said patented machine or of any other suitable type may be taken one at a time and stacked into successive piles of a predetermined number of products, each on a table or conveyor, the completed pile being moved out of the way in each instance to make room for the next succeeding pile.

In the preferred form of the invention, an endless conveyor is employed for receiving the successive stacks of unit strips, means being provided for lowering the receiving end of the conveyor progressively as the stack is formed. After the completion of each stack of units, automatically acting means serves to give the conveyor a single step of forward movement corresponding substantially to the size of the unit strips being stacked so as to provide a clear space on the conveyor for receiving the next succeeding pile of units. At substantially the same time when the conveyor is being advanced, the receiving end portion of the conveyor is moved upwardly to its uppermost receiving position for the start of the next pile of units. A novel form of clutch means is provided for controlling the action of the mechanism for raising and advancing the conveyor.

It is another object of this invention to improve machines of this type in sundry details hereinafter pointed out. The preferred means by which the several objects have been attained are illustrated in the accompanying drawings, in which—

Fig. 1 is a side face view of an improved machine embodying the invention;

Fig. 2 is a longitudinal vertical sectional view through the machine, taken substantially at the line 2—2 of Fig. 3;

Fig. 3 is a transverse vertical sectional view taken substantially at the line 3—3 of Fig. 1;

Fig. 4 is a vertical sectional view taken substantially at the line 4—4 of Fig. 3;

Fig. 5 is a sectional view taken substantially at the line 5—5 of Fig. 4;

Fig. 6 is a horizontal sectional view taken substantially at the line 6—6 of Fig. 7; and

Fig. 7 is a vertical sectional view taken substantially at the line 7—7 of Fig. 3.

Referring now to the several figures of the drawings, in which corresponding parts are indicated by the same reference characters, 10 indicates the framework of a unit strip machine having a shaft 11 rotatably mounted thereon and driven in clockwise direction in Fig. 1 from any suitable source of power, said shaft 11 in the preferred form of mechanism as illustrated being given a complete revolution for each delivery of a unit strip assembly by the unit strip machine. At an intermediate point along the shaft 11, a cam 12 is fixedly mounted thereon adapted to engage a roller 13 rotatably mounted on a pivotally mounted arm 14 so as to give the arm a downward stroke upon each revolution of the shaft. The arm 14 is preferably in the form of a channel, being pivoted in position by means of a transverse bar 15. At its free end, the arm 14 carries a crossbar 16, having links 17 connected therewith at their lower ends and connected at their upper ends with a bar 18 as shown in Fig. 3 for operating a cutting blade 19.

At opposite sides of the machine, standards 20 and 21 of a secondary framework are connected with the framework 10, as is best shown in Fig. 2, such standards being connected by side bars 22 with other standards 23, brace bars 24 being secured in oblique position for reinforcing the structure. Upon the secondary framework, an endless conveyor 25 is mounted by means of rollers 26 and 27, the roller 27 being supported on the standards 23 by means of a shaft 28, while the roller 26 is supported by means of a shaft 29 mounted on the upper ends of slide bars 30 rigidly connected together by means of a crossbar 31. As is best shown in Fig. 3, the slide bars 30 are mounted in position by means of slide bearings 32 carried by the standards 20 and 21. The arrangement is such that the end of the conveyor at the left in Figs. 1 and 2 is movable vertically with respect to the framework of the machine.

Means is shown for delivering unit strip assemblies from the unit strip machine as they are produced by the machine. This means comprises a suction device 33 of any suitable type operated through the medium of a lever 34 and a cooperating lever or link 35, by which the assemblies are moved into position above the rear end of the conveyor one at a time and there released so as to produce a pile or stack of the assemblies, the rear end portion of the conveyor (at the left in Fig. 1) being moved downwardly progressively as the machine operates for expediting the stacking of the assemblies. At predetermined intervals, the conveyor is brought back to its normal raised

position and is given a forward movement toward the right in Fig. 1 so as to provide room on the conveyor for the production of the next succeeding pile of the assemblies.

The means for moving the rear end portion of the conveyor 25 progressively downwardly comprises a shaft 36 which is driven by power from the shaft 11. During the normal operation of the machine at the time when a pile of the unit strip assemblies is being built up on the conveyor 25, the shaft 36 is driven intermittently by the shaft 11 by means of one set of driving connections, serving at this time to draw the rear end of the conveyor 25 downwardly. When a pile of the assemblies has been completed, an alternative set of driving means is thrown into operation for driving the shaft 36 from the shaft 11, serving under these circumstances to return the conveyor by a quick movement to its raised position and to advance the conveyor with the completed pile of assemblies thereon so as to make room for the production of another stack of assemblies on the conveyor.

The means for driving the shaft 36 intermittently from the shaft 11 comprises a link 37 connected with the shaft 11 eccentrically thereof by means of a pin 38, the opposite end of the link being pivotally connected with an arm 39 swingingly mounted on the shaft 36, a pawl 40 being pivotally mounted between the link and the arm in position to engage a ratchet wheel 41 fixedly mounted on the shaft 36. The arrangement is such that upon each revolution of the shaft 11 the pawl 40 gives the shaft 36 a slight rotary movement in counter clockwise direction in Fig. 1.

Means is provided for connecting the shaft 36 effectively with the crossbar 31 for moving such crossbar downwardly. This means comprises pinions 42 fixedly mounted on said shaft 36, meshing with gears 43 which are rotatably mounted on the standards 20 and 21. Each of the gears 43 is provided on its inner face with a pair of spaced undercut guides 44 between which a slide block 45 is slidably mounted, the arrangement being such that the blocks 45 are held rigidly in any desired adjusted position along the guides by means of set-screws 46 which are capable of being tightened against the faces of the gears 43, as is clearly shown in Fig. 5. The set-screws 46 serve also as means for pivotally connecting links 47 with the blocks 45, the links 47 being adjustably connected at their upper ends with the crossbar 31 so as to lift the rear end portion of the conveyor 25.

With the shaft 36 being given slight rocking movements intermittently in counterclockwise direction in Fig. 4 through the medium of the pawl 40 so as to rotate the gears 43 in clockwise direction in said figure, and with the blocks 45 connected in eccentric position with respect to said gears 43, the links 47 are given successive downward movements for moving the rear end portion of the conveyor 25 downwardly intermittently as a pile of unit strip assemblies is built up on the conveyor. The extent of movement of the conveyor downwardly is controlled by an adjustment of the eccentricity of the blocks 45 through the medium of the set-screws 46, so that the movement of the conveyor can be regulated to correspond to the thickness of the successive unit strip assemblies.

The means for driving the shaft 36 by power from the shaft 11 by the alternative set of driving means and for raising and advancing the conveyor comprises a shaft 48 rotatably mounted be-

10 tween the standards 20 and 21 immediately below the shaft 36 and directly in front of the shaft 11. A sprocket pinion 49 fixedly mounted on said shaft 48 is connected by a sprocket chain 50 with a sprocket gear 51 loosely mounted on the shaft 11, as is clearly shown in Fig. 6. This gear 51 is arranged to serve as a member of a clutch by which the gear can be connected with the shaft 11. To this end, the gear 51 has a pin 52 slidably mounted therein, a coiled spring 53 being provided bearing on the gear and the pin for applying yielding pressure on the pin for holding its end portion projected beyond the face of the gear into position to engage a cooperating clutch member 54 having a notch 55 in its face for receiving the end of the pin therein. The clutch member 54 is provided with a set-screw 56 for securing the member adjustably in fixed position on the shaft 11.

20 Below the shaft 11, two pivotally connected links 57 and 58 are mounted, the link 57 being pivotally mounted on the crossbar 15 and the link 58 being pivotally mounted on the shaft 48. A spring 59 normally holds the arm 57 in its raised position, with a roller 60 rotatably mounted on the arm engaging a bearing member 61 in the form of a large roller carried by the gear 51. The connections for the links 57 and 58 are loose enough to permit the arms to move downwardly 30 to a slight extent against the action of the spring 59 for carrying the arm 57 out of engagement with the pin 52 so as to permit the pin to be projected into operative position by the spring 53. When the arm 57 is lowered, the pin 52 engages the notch 55 so as to cause the gear 51 to rotate with the clutch member 54 and the shaft 11. When thereafter the arm 57 is moved upwardly again by the spring 59, the head of the pin 52 engages an obliquely positioned face portion 62 of the arm so as to force the pin lengthwise against the action of the spring 53 out of engagement with the notch 55.

35 The connecting means through which a connection is established between the shafts 48 and 36 comprises a pinion 63 fixedly mounted on the shaft 48 and meshing with a gear 64 which is rotatably mounted on the shaft 36. When the shaft 48 is driven by power from the shaft 11 in clockwise direction in Fig. 7, the gear 64 is driven in counterclockwise direction in said figure, serving through a ratchet wheel 65 and a pawl 66 to cause the shaft 36 to rotate also in counterclockwise direction, the ratchet wheel being fixedly mounted on the shaft 36 and the pawl 66 being pivotally mounted on the gear 64. A 40 spring 67 holds the pawl 66 normally in engagement with the ratchet wheel.

45 When the shaft 36 is being driven in counterclockwise direction in Fig. 1 from the shaft 11 through the medium of the ratchet wheel 65 and the pawl 40, the pawl 66 yields for permitting such rotation of the shaft 36 without correspondingly rotating the gear 64. When on the other hand the shaft 36 is being driven in said counterclockwise direction in Fig. 1 from the shaft 11 through the medium of the sprocket chain 50 and the pawl 66 as above described, the pawl 40 yields for permitting such rotation without putting any strain on the link 37 and its cooperating parts.

50 For bringing about an effective operation of the clutch comprising the pin 52 in the desired timed relation, an arm 68 is mounted rigidly on the arm 58 so as to extend about in front of the pinion 63 and thence upwardly in rear of

the shaft 36, being provided at its upper end with a pin portion 69 extending longitudinally of the shaft 36 into position to be engaged by a pin 70 extending from the face of the gear 43 at that side of the machine. The arrangement is such that when the pin 70 in the rotation of the gear 43 in clockwise direction in Fig. 4 comes into engagement with the pin 69 the arm 58 is forced downwardly, serving to move the arm 57 also downwardly for causing the clutch to be thrown into operation. The gear 43 is then driven through the chain 50 and its cooperating parts including the pawl 66 so as to carry the pin 70 quickly out of engagement with the pin 69, whereupon the arm 57 quickly moves upwardly into position to throw the pin 52 out of operative engagement with the notch 55 of the clutch member 54 as soon as said pin 52 engages the obliquely positioned face portion 62 of said arm 57.

As will be readily understood, when the gears 43 are being driven in clockwise direction in Fig. 4 by the clutch mechanism and its cooperating parts, such gears 43 serve through the links 47 to raise the slide bars 30 for carrying the rear end portion of the conveyor 25 again to its uppermost operative position substantially as shown in Fig. 2. At the same time, the shaft 48 rotating in unison with the shaft 11 serves through a sprocket gear 71, a chain 72, and a sprocket gear 73 to move the top ply of the conveyor belt 25 a short distance toward the right in Fig. 1 for moving the pile of unit strip assemblies out of the way for permitting the formation of a new pile.

The arrangement is such that the clutch comprising the pin 52 is thrown into operation in every instance when the pin 70 on the gear 43 is brought to its lowermost position. This insures that the conveyor is moved downwardly by intermittent movements through the medium of the link 37 and pawl 40 and is given a quick upward movement through the medium of the clutch as above described. The timing of the action of the clutch is thus controlled by the rotation of the gear 43 which in turn is controlled by the relative sizes of the pinion 42 and the gear 43. These parts are preferably of such relative size as to insure that the gears 43 shall be given one complete revolution for every twenty-five revolutions of the shaft 11. Since a unit strip assembly is delivered at each revolution of the shaft 11, it will be appreciated that each of the piles of assemblies will contain twenty-five units, under the conditions specified. If a different size of gear 43 and pinion 42 are employed, so as to change the relative sizes of these parts and thus change the number of units in the individual piles, the uniformity in size and in the number of the units will nevertheless be maintained from one pile to the next during normal operation of the machine.

While the form and arrangement of the parts as illustrated are preferred, the invention is not to be limited thereto except as the claims may be so limited, it being understood that changes might well be made in the form and arrangement of the parts without departing from the spirit of the invention.

I claim:

1. In a stacking mechanism, the combination of a conveyor of a length for receiving a plurality of articles in spaced relation along the conveyor and movable both horizontally and vertically in position to receive a series of articles

one at a time for arrangement in piles thereon and adapted to carry each pile forwardly when completed so as to make way for subsequent piles, means for giving the conveyor successive downward movements at intervals for keeping the top face of a growing pile of articles at substantially the same height, and means thrown into operation when the conveyor reaches a predetermined lowered position to give the conveyor a return movement upwardly.

5 2. In a stacking mechanism, the combination of a conveyor of a length for receiving a plurality of articles in spaced relation along the conveyor and movable both horizontally and vertically in position to receive a series of articles one at a time for arrangement in piles thereon and adapted to carry each pile forwardly when completed so as to make way for subsequent piles, means for giving the conveyor successive downward movements at intervals for keeping the top face of a growing pile of articles at substantially the same height, and means adapted when the conveyor has been given a predetermined number of downward movements to give the conveyor a forward movement horizontally for providing room for the succeeding pile in backwardly spaced relation to the first-mentioned pile and at the same time to return the conveyor to its uppermost raised position for starting the next pile.

20 3. In a stacking mechanism, the combination of a conveyor of a length for receiving a plurality of articles in spaced relation along the conveyor and movable both horizontally and vertically in position to receive a series of articles one at a time for arrangement in piles thereon and adapted to carry each pile forwardly when completed so as to make way for subsequent piles, means for giving the conveyor successive downward movements at intervals as said articles are delivered to the conveyor, means for adjusting the action of said means for moving the conveyor downwardly so as to make each downward movement correspond with the thickness of one 25 of said articles and thus to keep the top face of the growing pile of articles at substantially the same height, and means adapted when the conveyor has been given a predetermined number of downward movements to give the conveyor upward and forward movements into position to receive the next pile of articles.

45 4. In a stacking mechanism, the combination of a conveyor movable both horizontally and vertically in position to receive a series of articles one at a time for arrangement in piles thereon and adapted to carry each pile forwardly when completed so as to make way for subsequent piles, means comprising a rotatably mounted member adapted at one portion of each revolution to move the conveyor downwardly and adapted at the remaining portion of each revolution to return the conveyor to its raised position, driving means for giving said member a step by step movement through the portion of the revolution by which the conveyor is moved downwardly, other driving means for giving said member a comparatively much quicker movement through the portion of the revolution by which the conveyor is moved upwardly, and means actuated in timed relation to the operation of the machine for shifting periodically from one driving means to the other.

50 5. In a stacking mechanism, the combination of a conveyor movable both horizontally and

vertically in position to receive a series of articles one at a time for arrangement in piles thereon and adapted to carry each pile forwardly when completed so as to make way for subsequent piles, means comprising a rotatably mounted member adapted at one portion of each revolution to move the conveyor downwardly and adapted at the remaining portion of each revolution to return the conveyor to its raised position, means comprising a pawl and ratchet mechanism actuated by a reciprocatory link for giving said member a step by step movement through the portion of the revolution by which the conveyor is moved downwardly, and means comprising a clutch automatically thrown into operation when a pile is completed for moving said member through the portion of the revolution by which the conveyor is moved upwardly.

6. In a stacking mechanism, the combination of a conveyor movable both horizontally and vertically in position to receive a series of articles one at a time for arrangement in piles thereon, means comprising a rotatably mounted member adapted at one portion of each revolution to move the conveyor downwardly and adapted at the remaining portion of each revolution to return the conveyor to its raised position and to give the conveyor a slight movement forwardly for providing room for the succeeding pile, means for giving said member a step by step movement through the portion of its revolution by which the conveyor is moved downwardly, and means comprising a clutch automatically thrown into operation at the completion of each pile in turn for giving said member a comparatively much quicker movement through the portion of the revolution by which the conveyor is moved upwardly and forwardly.

7. In a stacking mechanism, the combination of a frame, two rollers rotatably mounted on said frame in horizontally spaced relation to each other with one of said rollers movable vertically on the frame, an endless belt conveyor on said rollers in position to receive a series of articles one at a time for arrangement in piles on the conveyor and adapted to carry each pile forwardly when completed so as to make way for subsequent piles, a member rotatably mounted on said frame below said vertically movable roller, a link pivotally connected between said rotatable member and said movable roller and adjustable radially with respect to said rotatable member for controlling its eccentricity with respect thereto, means for giving said rotatable member a step by step movement through a portion of each revolution for moving the conveyor downwardly, and means for giving said rotatable member a comparatively much quicker movement through the remaining portion of each revolution for moving the conveyor upwardly.

8. In a stacking mechanism, the combination of a conveyor movable vertically in position to receive a series of articles one at a time for arrangement in piles thereon and adapted to carry each pile forwardly when completed so as to make way for subsequent piles, a member rotatably mounted on a transverse axis below said conveyor, means comprising a pawl and ratchet mechanism for giving said rotatable member a slight rotary movement upon each delivery of an article to the conveyor for stacking, connections between said rotatable member and said conveyor for giving said conveyor a slight downward movement upon each actuation

5 of the rotatable member by said pawl and ratchet mechanism and adjustable toward and from the axis of said rotatable member for varying the extent of vertical movement of the conveyor thereby, and other means adapted to act automatically when a predetermined number of articles have been delivered to the conveyor to return the conveyor to its raised position.

9. In a stacking mechanism, the combination 10 of a conveyor movable vertically in position to receive a series of articles one at a time for arrangement in piles thereon and adapted to carry each pile forwardly when completed so as to make way for subsequent piles, a member 15 rotatably mounted on a transverse axis below said conveyor, means comprising a pawl and ratchet mechanism for giving said rotatable member a slight rotary movement upon each delivery of an article to the conveyor for stacking, connections between said rotatable member and said conveyor for giving said conveyor a slight downward movement upon each actuation of the rotatable member by said pawl and ratchet mechanism and adjustable toward and from the 20 axis of said rotatable member for varying the extent of vertical movement of the conveyor thereby, and other means comprising a clutch mechanism actuated automatically when a predetermined number of articles have been stacked 25 in a pile for moving the conveyor upwardly to its raised position and actuated automatically at the end of the upward movement of the conveyor for opening the clutch.

10. In a stacking mechanism, the combination 30 of a conveyor movable vertically in position to receive a series of articles one at a time for arrangement in piles thereon and adapted to carry each pile forwardly when completed so as to make way for subsequent piles, a shaft, means 35 actuated by the rotation of said shaft for moving said conveyor vertically, a second shaft rotating in timed relation to the delivery of articles to said conveyor, means comprising a pawl and ratchet mechanism for driving said first-named shaft intermittently by power from said second shaft and arranged for permitting said second shaft to be driven in the same direction independently of said pawl and ratchet mechanism, and means comprising a clutch and a second 40 pawl and ratchet mechanism for driving said first-named shaft alternatively by power from said second shaft independently of said first-named driving means and arranged for permitting said second shaft to be driven by the first-named pawl and ratchet mechanism without undue strain on said second-named driving means.

11. In a stacking mechanism, the combination 45 of a conveyor movable vertically in position to receive a series of articles one at a time for arrangement in piles thereon and adapted to carry each pile forwardly when completed so as to make way for subsequent piles, a shaft, means 50 actuated by the rotation of said shaft for moving said conveyor vertically, a second shaft rotating in timed relation to the delivery of articles to said conveyor, means comprising a pawl and ratchet mechanism for driving said first-named shaft intermittently by power from said second shaft and arranged for permitting said second shaft to be driven in the same direction independently of said pawl and ratchet mechanism, means comprising a clutch and a second pawl and ratchet mechanism for driving said first-named shaft alternatively by power from said 55

second shaft independently of said first-named driving means and arranged for permitting said second shaft to be driven by the first-named pawl and ratchet mechanism without undue strain on said first-named driving means, and means actuated in timed relation to the delivery of articles to said conveyor for throwing said clutch automatically into and out of operation for causing the first-named driving means to be effective for moving the conveyor downwardly and causing the second-named driving means to be effective for moving the conveyor upwardly.

12. In a stacking mechanism, the combination of a conveyor movable vertically in position to receive a series of articles one at a time for arrangement in piles thereon and adapted to carry each pile forwardly when completed so as to make way for subsequent piles, a shaft, means actuated by the rotation of said shaft for moving said conveyor vertically, a second shaft rotating in timed relation to the delivery of articles to said conveyor, means comprising a pawl and ratchet mechanism for driving said first-named shaft intermittently by power from said second shaft and arranged for permitting said second shaft to be driven in the same direction independently of said pawl and ratchet mechanism, means comprising a clutch and a second pawl and ratchet mechanism for driving said first-named shaft alternatively by power from said second shaft independently of said first-named driving means and arranged for permitting said second shaft to be driven by the first-named pawl and ratchet mechanism without undue strain on said first-named driving means, means comprising an arm swingingly mounted adjacent to said clutch mechanism adapted on a movement of the arm away from the clutch to throw the clutch into effective operation for moving the conveyor upwardly and adapted on a movement of the arm thereafter toward the clutch to throw the clutch out of effective operation, and means controlled by the movement of the conveyor downwardly for giving said arm a stroke away from the clutch when a predeter-

mined number of articles have been delivered to the conveyor for stacking.

13. In a stacking mechanism, the combination of a conveyor movable vertically in position to receive a series of articles one at a time for arrangement in piles thereon and adapted to carry each pile forwardly when completed so as to make way for subsequent piles, a shaft, means comprising rotatable members at opposite sides 10 of the machine actuated by the rotation of said shaft for moving said conveyor vertically, a second shaft rotating in timed relation to the delivery of articles to said conveyor, means comprising a pawl and ratchet mechanism for driving said first-named shaft intermittently by power from said second shaft and arranged for permitting said second shaft to be driven in the same direction independently of said pawl and ratchet mechanism, means comprising a clutch and a second pawl and ratchet mechanism for driving said first-named shaft alternatively by power from said second shaft independently of said first-named driving means and arranged for permitting said second shaft to be driven by the first-named pawl and ratchet mechanism without undue strain on said second-named driving means, means comprising an arm swingingly mounted adjacent to said clutch mechanism adapted on a movement of the arm away from the clutch to throw the clutch into effective operation for moving the conveyor upwardly and adapted on a subsequent movement of the arm toward the clutch to throw the clutch out of effective operation, a pin extending from the face of one of said rotatable members, and a second arm movably mounted in position to be engaged by said pin at the end of the downward movement of the conveyor so as to be displaced thereby and adapted when so displaced to give said first-named arm a stroke away from the clutch for causing the clutch to be thrown into effective operation for moving the conveyor upwardly.

ROBERT ALONZO WILLIAMS.
